WALTER EDWIN TRENT, OF NEW YORK, N. Y., ASSIGNOR TO TRENT PROCESS CORPORATION, OF NEW YORK, N. Y., A CORPORATION OF DELAWARE

CARBONIZING PROCESS

Application filed February 27, 1925. Serial No. 12,128.

The invention relates to a process of and apparatus for, carbonizing or coking comminuted coal, or mixtures of coal and hydrocarbon oils.

5 It is an object of the invention to provide a process in which coal or coal and oil mixtures or liquid hydrocarbons are carbonized while in a receiver or pan by heat applied thereto by heat storing elements disposed in 10 heat conductive contact with the receiver, thereby eliminating the application of combustion gases directly to the materials being treated.

More specifically, the invention contemplates a process of this type wherein bulk 15 quantities of coal or coal and oil or oil are moved through a distilling, carbonizing or coking zone while in heat conductive relation with removable heat storage elements 20 heated to a definite temperature when disposed adjacent the conveyor to apply a determined quantity of heat to the materials being treated.

In accordance with the present process the 25 materials being treated may be carbonized, or if a coking coal is used these materials can form a coke mass, the density and strength depending upon the rate of heat transfer to the mass and to the applied tem- 30 perature.

In the drawings,—

Figure 1 represents a view partly in longitudinal vertical section and partly in side elevation of an apparatus capable of carrying 35 out this process.

Fig. 2 is a sectional view of the pan.

Fig. 3 is a view of a slightly modified form of pan.

Referring now more particularly to the 40 drawings, in which I have shown somewhat diagrammatically an apparatus that may be successfully used, the numeral 1 designates a carbonizing or coking chamber. This chamber has a sprocket 2 therein, around which 45 an endless conveyor 3 carrying the metallic pans 4 passes. The conveyor at its opposite end passes around a sprocket wheel 5 located exteriorly of the carbonizing chamber and at this point the pans 4 receive their bulk 50 charges of coal or plastic mixtures of coal and

oil. The conveyor with the pans passes through apertures 6 in the wall of the distilling chamber and through these apertures some air may be permitted to enter the interior of the chamber as I have found that oxygen is needed to carbonize the material. When working at low temperatures, if case-hardening or only semi-carbonization of coal oil mixtures is wanted, a limited amount of oxygen promotes the result to be desired. 55

Referring now more particularly to the pans 4, it will be observed that each pan has a bottom pocket 7 formed therein, constituting a receiver for a heat storage element 8 composed of cast iron or any other suitable 60 metal. The pans, of course, have the wall 9 separating the heat storage element from the material in each pan. In operation the heat storage elements 8 are heated in a furnace or the like and as the conveyor moves 65 out of the distilling chamber 1 a cool element is removed from the pocket beneath the pan and a hot element substituted in lieu thereof. At this time a green charge of material is placed in the pan and the pan with 70 its charge then enters and passes through the distilling or carbonizing chamber 1. During the travel of the pan through this chamber the heat from the storage element carried thereby passes through the bottom wall of 75 the pan at a determined and regulated rate, slowly applying heat to the bulk material 80 a in each pan, causing the same to carbonize. The coal particles in some instances will form a coherent mass, particularly if coking coal 85 is used, or if a mixture of coal and oil is used and if the temperature and time of treatment are regulated.

If the charge is subjected to a high temperature and the wall of the pan and size and 90 temperature of the heat storage element is suitably designed to give up its heat in the least possible time, the mass will be distilled at the maximum rate and both gases and condensable vapors will result and at times this 95 type of operation is desirable when the final form of the solid carbonized residue is not required to be either hard or dense. Such an operation is often desirable in order to obtain a soft, friable, carbonized mass later to 100

be pulverized or re-made into specification solids.

The material passes through the distilling chamber and as each pan passes around the sprocket 2 the treated material discharges into a trough 10 in communication with an outlet conduit 11 leading to the exterior of the distilling zone. This conduit may be controlled by a gate valve 12. Gases and vapors generated in the distilling chamber are discharged through the pipes 13 communicating with the header 14 and collected for subsequent treatment and use.

In accordance with this process it will be observed that bulk supplies of material can be fed to the pans as they enter the distilling chamber and at the same time the heat storage elements are also placed beneath each filled pan. These heat storage elements can be heated to various temperatures depending upon the product desired. For a partial carbonization low temperature carbonization of the coal can be effected, and when such an operation is being practiced, the heat storage elements are heated to a temperature sufficient to raise the temperature of the coal to, say, 600° centigrade. If the coal, however, is to be dry-coked or entirely carbonized, the heat storage elements are heated to raise the temperature of the coal to 800° or 900° centigrade. Gases and vapors driven from the coal are discharged through the lines 13 and 14 for subsequent treatment and collection.

The treated product remaining in the various pans after their travel from the inlet to the distilling zone to the sprocket 2 is discharged into the receiving trough 10 and this carbonized product is then withdrawn from the chamber as desired through the manipulation of the valve disposed in the outlet conduit leading from the discharge trough.

It will be apparent that in carrying out this process any form of apparatus can be used. It is not necessary that the pans be movable as the heat storage elements can be applied to stationary receivers into which coal is deposited, and it will be appreciated that the apparatus herein disclosed has merely been shown for the purpose of illustrating one type of apparatus which will support the process. The heat storage elements can also be constructed of any desired material, and any suitable means may be employed for removing and inserting the elements into the pockets formed in the pans.

In the modified structure shown in Fig. 3, I provide a pan in which the false bottom is eliminated. In this structure I place the heat storage elements directly on the base of the pan and retain these elements in position by retaining channels 7' beneath which the heat storing elements slide. In this process the fuel charges are introduced directly on the heat storing elements.

Having thus described the invention, what I claim is:

1. A carbonizing process comprising progressively advancing through a distilling zone a series of containers, introducing a predetermined charge of carbonaceous fuel matter to each container, providing for each container a removable storage element of a size sufficient to store heat units required to carbonize the fuel charge of each container, heating each element to a predetermined temperature before application to its container and moving said elements through the distilling zone with the containers to effect carbonization of fuel charges in the containers solely by the heat radiating from said heat storage elements.

2. A carbonizing process comprising progressively advancing through a distilling zone a series of containers, introducing a predetermined charge of carbonaceous fuel matter to each container, introducing to each container beneath said charge and in heat transferring relation thereto a storage element of a size sufficient to store heat units required to carbonize the fuel charge of each container, heating each element to a predetermined temperature before application to its container and moving said elements through the distilling zone with the containers to effect carbonization of fuel charges in the containers solely by the heat radiating from said heat storage elements.

3. A carbonizing process comprising providing a series of containers and a heated element for introduction to each of said containers, heating said elements to a temperature sufficient to carbonize fuel charges placed therein without the application of additional heat thereto, introducing said elements to said containers, introducing carbonaceous fuel to the series of containers in contact with said elements, progressively advancing said containers through a distilling zone, and successively discharging the containers within said zone.

4. An apparatus for use in the heat treatment of carbonaceous materials comprising an endless conveyor, a distilling zone enclosure enclosing a substantial portion of the upright run of the conveyor and having means to discharge volatiles therefrom, bulk supply receptacles mounted at spaced intervals on said conveyor each having a hole in the side wall near the bottom thereof and adapted to receive a bulk supply of carbonaceous material prior to its entry in the said enclosure, a hopper for receiving the residue from the receptacles at the dumping end of said conveyor within said enclosure, and heat transferring plates insertable through said holes in heat transferring relationship with said bulk supply and adapted to give up heat to the carbonaceous materials constituting said bulk supply during the pas-

sage of each individual receptacle through the distilling zone.

5. An apparatus for use in the heat treatment of carbonaceous materials comprising an endless conveyor, a distilling zone enclosure enclosing a substantial portion of the upright run of the conveyor having means to discharge volatiles therefrom, bulk supply receptacles mounted at spaced intervals on said conveyor and adapted to receive a bulk supply of carbonaceous material prior to their entry to the said enclosure, a hopper for receiving the residue from the receptacles at the dumping end of said conveyor within said zone, and heat transferring elements adapted to be heated and to store sufficient heat to carbonize the bulk supply in each receptacle during its passage through said enclosure, and means for maintaining such an element in each receptacle in heat transferring relationship with said bulk supply during the passage of each individual receptacle through the distilling zone.

6. In an apparatus for carbonizing fuels, the combination with a conveyor, a distilling chamber enclosing a substantial part of said conveyor, means on the conveyor for carrying bulk supplies of carbonaceous fuel, heat transferring elements adapted to be heated and to store sufficient heat to carbonize the bulk supplies of fuel on the conveyor during passage thereof through the distilling chamber, and means for removably supporting said heat transferring elements on said conveyor in heat transferring relationship with said supplies of fuel during passage through the distilling chamber, and means for receiving and discharging the products of carbonization produced in said distilling chamber.

40 In testimony whereof I affix my signature.
WALTER EDWIN TRENT.
